HANGER

Fred Schoen, 1/2 Sun Clothes, Inc., 26th and Reed Sts., and Tony M. San Felice, 1/2 Fishman & Tobin, Inc., Broad and Carpenter Sts., both of Philadelphia, Pa. 19147

Filed Dec. 6, 1965, Ser. No. 511,592
2 Claims. (Cl. 223—95)

This invention relates in general to clothes hangers and is more particularly directed to an adjustable type of pants hanging and stretching device.

The instant invention incorporates a pair of hollow, parallel supports respectively carrying depending cuff grippers to engage the cuffs of a pair of boys' or men's trousers. By imparting spring biased mobility to one of the grippers along the longitudinal axis of each support, a convenient method of accommodating trouser cuffs of all sizes may be realized. In addition to simply hanging a pair of trousers, the instant invention finds utility in the garment industry during the finishing process. The spring biased grippers engage the inside of the cuffs and stretch them as required for even curing during a permacrease process.

Prior art hangers as presently available are usually constructed of wire or wood or combinations thereof. One well-known type grips the trousers externally thereof near the cuffs to conveniently hang the garment from a pole or hook. However, such a device merely holds the trousers and offers no method of stretching them as is sometimes required. Other hangers are formed from bent wire and externally engage the trousers under the cuffs. Such hangers serve a useful purpose but are severely limited in utility in their inability to accommodate trousers of varying cuff widths. Further, in accordance with style trends, many pants are presently manufactured and finished completely without cuffs and in such styles, the bent wire type of hanger is completely useless.

It is therefore an object of this invention to provide a novel hanger that is suitable for use with trousers of varying cuff widths.

It is another object of this invention to provide a novel hanger that is suitable for use with trousers of either the cuffed or cuffless styles.

It is another object of this invention to provide a novel pants hanger incorporating means to automatically adjust the overall distance between grippers as required by the size trousers to be hung.

It is another object of this invention to provide a novel pants hanger that may be readily varied in overall length as required to accommodate trousers of different cuff widths.

It is another object of this invention to provide a novel pants hanger featuring both movable and immovable portions suitable for gripping a pair of trousers near the cuffs thereof.

It is another object of this invention to provide a novel pants hanger incorporating a pair of mobile, spring-biased grippers carrying extended, manually operated handles for ready operation with trouser cuffs of varying widths.

It is another object of this invention to provide a novel pants hanger that is rugged in construction, inexpensive in manufacture and trouble free in operation.

Other objects and a fuller understanding of the invention will be had by referring to the following description and claims of a preferred embodiment thereof, taken in conjunction with the accompanying drawing wherein like reference characters refer to similar parts throughout the several views and in which:

FIG. 1 is a front perspective view showing the hanger in hanging engagement with a pair of trousers.

2

FIG. 2 is an enlarged front perspective view of a hanger constructed in accordance with the instant invention.

FIG. 3 is a sectional view taken along line 3—3 of FIG. 2.

FIG. 4 is a sectional view taken along line 4—4 of FIG. 3.

FIG. 5 is a front perspective view, partially broken away to expose the interior construction, of a modified form of the instant invention.

FIG. 6 is a sectional view taken along line 6—6 of FIG. 5.

FIG. 7 is a sectional view taken along line 7—7 of FIG. 6.

Although specific terms are used in the following description for the sake of clarity, these terms are intended to refer only to the particular structure of our invention selected for illustration in the drawings and are not intended to define or limit the scope of the invention.

Referring now to the drawings, we show a pair of hollow, elongated supports 10, 12 rigidly held in spaced, parallel relationship by a transverse yoke 14. The yoke 14 may conveniently be fabricated from a flat steel bar and then secured as required to the tops of the respective supports 10, 12. A bent wire hanger 16 medially carries the yoke 14 and permits ready suspension of the entire assembly A from any suitable rod, line or similar support by engagement with the bent upper section.

As best seen in FIGS. 2, 3, 4, the supports 10, 12 are formed of elongated, square tubing and each carries a stationary, depending cuff gripper 18, 20 at the respective closed end 22, 24 thereof. The stationary grippers may be secured to the supports in any well-known manner such as by welding as at 26, 28.

A pair of movable cuff grippers 30, 32 depend from similar rectangular blocks 34, 36 which slide within the respective channels 38, 40 defined by the rectangular supports 10, 12. Longitudinal slots 50, 52 medially divide the respective bottoms of the supports 10, 12 to receive the cuff grippers 30, 32 which depend therethrough and thus permit longitudinal movement of the cuff grippers as hereinafter more fully set forth. The blocks 34, 36 are continuously urged away from the respective stationary cuff grippers 18, 20 by coil springs 42 acting within the channels 38, 40. As shown in FIG. 3, the stationary end 46 of the spring 42 contacts the closed end 24 of the support 12 and the action end 44 contacts the block 36 and biases the block and its attached cuff gripper 32 away from the stationary gripper 20.

The utility of the construction may be readily observed by reference to FIG. 1 wherein a pair of trousers 48 are shown being supported at the cuffs by the hanger assembly A. It can be readily observed that the roughened outboard surfaces 54, 56, 58, 60 of the respective cuff grippers 30, 18, 32, 20 contact the interior of the trouser cuffs and hang the trousers from this position. The springs 42 must be compressed as necessary to permit the movable cuff grippers 30, 32 to be adjusted to accommodate the width of the trouser cuffs. The bias of the springs 42

urge the cuff grippers 30, 32 outwardly and thus assure secure contact between the hanging assembly A and the trousers 48. In this manner, a sturdy hanging arrangement is provided with positive, spring-biased contact between the hanger and the trousers assured at all times.

Even relatively heavy trousers may be so hung without danger of the trousers dropping free of the cuff gripper contact.

In FIGS. 5, 6 and 7, we show a modified type of hanger construction utilizing a pair of spaced, rectangular or cylindrical tube supports 10, 12 secured by a horizontal connecting yoke 14. A bent wire hanger 16 may be swiv-

ed to the yoke 14 and permits ready suspension of the entire assembly A from any suitable rod, line or similar support by engagement with the bent upper section.

The utility of the construction may be readily observed by reference to FIG. 1 wherein a pair of trousers 48 are shown being supported at the cuffs by the hanger assembly A. It can be readily observed that the roughened outboard surfaces 54, 56, 58, 60 of the respective cuff grippers 30, 18, 32, 20 contact the interior of the trouser cuffs and hang the trousers from this position. The springs 42 must be compressed as necessary to permit the movable cuff grippers 30, 32 to be adjusted to accommodate the width of the trouser cuffs. The bias of the springs 42

urge the cuff grippers 30, 32 outwardly and thus assure secure contact between the hanging assembly A and the trousers 48. In this manner, a sturdy hanging arrangement is provided with positive, spring-biased contact between the hanger and the trousers assured at all times.

elly secured to the yoke 14 intermediate its connection to the supports 10, 12 to permit easy hanging of the assembly A either when in use or when being stored for future use. The movable cuff grippers 30, 32 depend from rectangular or cylindrical blocks 34, 36 and extend downwardly through the bottom positioned slots 50, 52 which are provided to permit longitudinal movement of the cuff grippers 30, 32 along the supports 10, 12. A pair of finger pulls 62, 64 project upwardly from the movable blocks 34, 36 and are diametrically opposed to the cuff grippers 30, 32. The finger pulls ride longitudinally along the supports 10, 12 in the upper slots 66, 68 and provide easy operation of the grippers 30, 32 simply by grasping the pulls 62, 64 and urging them longitudinally against the bias of the compression springs 42.

In the instant modification, the stationary grippers 70, 72 depend from the support encircling clamps 74, 76 and have longitudinal adjustment along one half of the supports 10, 12. Set screws 78, 80 of the well-known wing nut variety, permit easy adjustment of the position of the stationary grippers 70, 72 along the length of the supports as required to accommodate the width of the cuffs of the trousers being processed. If desired, a plurality of position lines 82 may be scribed or otherwise marked on the top exterior of the supports to permit visual equal adjustment of the grippers 70, 72.

In order to use our invention, the stationary cuff grippers 18, 20 should be interiorly engaged respectively with the cuffs of a pair of trousers 48. The movable grippers 30, 32 may then be individually urged towards the stationary support ends 22, 24 against the bias of the springs 42 until the distance between gripper surfaces 54, 56 and 58, 60 is less than the width of the trouser cuffs. The grippers 30, 32 are then inserted within the trouser cuffs and released, thereby permitting the springs 42 to push the surfaces 54, 56 and 58, 60 into a slip-proof engagement with the cuffs.

The above procedure may be similarly followed with the modified hanger of FIG. 5, with the exception that the finger pulls 62, 64 may more conveniently be employed to move the grippers 30, 32 against the bias of the springs 42. Also, the set screws 78, 80 may be utilized to vary the initial distance between the grippers 30, 70 and 32, 72 as required to accommodate various sized cuffs.

Although we have described our invention with a certain degree of particularity, it is understood that the present disclosure has been made only by way of example and that numerous changes in the details of construction and the combination and arrangement of parts may be resorted to without departing from the spirit and scope of the invention as hereafter claimed.

What is claimed is:

1. A hanger for supporting a pair of trousers by the cuffs thereof, the combination of
5 a pair of hollow, parallel, elongated horizontal supports, a rigid yoke, said yoke being interconnected between the said supports and spacing the said supports in parallel arrangement, said supports each being provided with a bottom, longitudinal slot, and said supports each being provided with a top, longitudinal slot, said bottom and top slots each extending a substantial distance from and along the length of one end of each support;
10 an adjustably fixed vertically elongated cuff gripper affixed about the other end of each of the said supports, means to fixedly position the said fixed cuff gripper in any of many alternative locations along the said support, said means including a set screw operatively turned through the said gripper onto the said support securing the said gripper to the said support;
15 a movable cuff gripper slidably carried at said one end of each of said supports, said cuff grippers depending through the said bottom slots;
20 gripper operating means extending above said movable grippers, said operating means extending through the said top slots;
25 an operating spring in each of said elongated supports biasing each of the said movable cuff grippers away from the said fixed cuff grippers, and
30 a hanger hook member secured medially of said yoke.
2. A hanger as defined in claim 1 wherein each of said supports includes a plurality of markings on the top surface of said other end with each marking on one of said supports being in alignment with a respective marking on the other of said supports to permit visual equal adjustment of said adjustably fixed cuff grippers.
